Fig. 5

Fig. 6

FIG. 1 is a plan view of a brassiere showing my new design;

FIG. 2 is a plan view of the side opposite that shown in FIG. 1;

FIG. 3 is a bottom plan view thereof;

FIG. 4 is a top plan view;

FIG. 5 is a side elevational view; and

FIG. 6 is an enlarged front elevational view.

The essential feature of my design lies in the combination on the brassiere disclosed of the two horizontally disposed bands of material positioned horizontally beneath the bust cups, and interconnected along the longitudinal edges thereof by lattice work stitching as best seen in FIG. 6.

I claim:

The ornamental design for a brassiere, substantially as shown and described.
